UNITED STATES PATENT OFFICE.

WILLIAM A. SCHLEICHER, OF CLEVELAND, OHIO.

DESIGN FOR A VEHICLE-STEP.

SPECIFICATION forming part of Design No. 21,191, dated December 1, 1891.

Application filed October 30, 1891. Serial No. 410,407. Term of patent 14 years.

To all whom it may concern:

Be it known that I, WILLIAM A. SCHLEICHER, of Cleveland, in the county of Cuyahoga and State of Ohio, have invented a new and original Design for Steps for Vehicles, of which the following is a full, clear, and exact description, reference being had to the accompanying photograph, forming part of this specification, which shows in plan view the surface or pad of a vehicle-step embodying my design.

The design consists of a vehicle-step having a surface configuration substantially as herein shown and described. The step surface or pad is of substantially circular form, and has

a diagonal band or stripe *a*, provided with series of adjacent figures. At the sides of this band, within the circular outline of the step, are figured portions *b b'*.

I claim—

The design for vehicle-steps, substantially as herein shown and described.

In testimony whereof I have hereunto set my hand this 7th day of October, A. D. 1891.

WILLIAM A. SCHLEICHER.
